UNITED STATES PATENT OFFICE.

LOUIS DE OLIVA DEOL, OF NEW YORK, N. Y.

ORTHOPEDIC CUSHION.

1,154,491.

Specification of Letters Patent. Patented Sept. 21, 1915.

Application filed May 15, 1915. Serial No. 28,374.

To all whom it may concern:

Be it known that I, LOUIS DE OLIVA DEOL, a citizen of Argentina, and a resident of the city of New York, borough of Manhattan, in the county and State of New York, have invented a new and Improved Orthopedic Cushion, of which the following is a full, clear, and exact description.

Among the principal objects which the present invention has in view are: to provide an orthopedically shaped surface generally conforming to the curvatures of the normal human foot; to provide means for softening the jar incident to the operation 15 of walking; to provide means concealed within the shoe for increasing the apparent height of a human being; to correct the manner of walking of the wearer; and to form a comfortable and natural support for 20 the arch of the foot.

Drawings.—Figure 1 is a side edge view of a cushion constructed and arranged in accordance with the present invention, said cushion being shown in conjunction with a 25 shoe and the outline of a human foot, and as under compression; Fig. 2 is a cross section taken as on the line 2—2 in Fig. 1, the view showing the cushion as under service compression; Fig. 3 is an edge view of the 30 cushion shown as detached from a shoe; Fig. 4 is a longitudinal section taken as on the line 4—4 in Fig. 3; Fig. 5 is a view similar to that shown in Fig. 2, the difference being that the cushion is not under 35 compression; and Fig. 6 is a detail view showing the reinforce with which the cushion is provided for stiffening the side walls thereof.

Description.—As shown in the drawings, 40 the cushion 12 is hollow, the walls thereof being made to form a closed chamber 13, the device extending from a point at the rear of the heel of the wearer to a point slightly in advance of the toes. As seen 45 best in Fig. 3 of the drawings, the cushion is particularly thick from the arch 14 backward to the rear of the heel 15, the maximum thickness of this portion of the cushion being approximately the same. Forward of 50 the arch 14 is a sloping and relatively thinner portion 16.

From the foregoing and by observation of the drawings, it will be seen that the rear portion of the cushion is much thicker than 55 the forward portion, the intention being to lift the heel of the wearer to produce that

effect which is generally known as being slightly on tip-toe. The immediate result of supporting the body of the wearer on an appliance so constructed is to provide an 60 orthopedically shaped, resilient surface for a normal human foot to rest upon, thereby adding greatly to the well-being of the nervous system of the wearer and the general well-being of his entire body; and also to 65 increase the apparent height of the wearer without increasing the height of the heel of the shoe. The latter method of increasing the apparent height of the person is so obvious as to draw a certain amount of odium 70 on the wearer.

As best seen in Figs. 4 and 5 of the drawings, the side walls of the rear portion of the cushion are either thick or else are reinforced, this being preferably accomplished 75 by incorporating in the side wall structure a strengthening material 19 stiffer than the material forming the side wall of the cushion. The result of such construction is that, when the weight of the foot is transferred 80 to the cushion, the strengthening material 19 of the side walls thereof restrains the cushion from collapsing, thereby imparting a firmer rest and tread to the foot.

With the cushion constructed and ar- 85 ranged as shown in the accompanying drawings and as herein described, the air in the chamber 13 is lastingly inclosed. When the shoe equipped with the cushion is placed on the foot, the air within the cham- 90 ber 13 is relatively cool, and the dimensions of the cushion are normal. When the foot is placed within the shoe, to rest upon the cushion, the air becomes warmer, and slightly expands said cushion. This action 95 of the air in the cushion results in conforming the foot more neatly and closely to the shoe.

As shown best in Figs. 2 and 5 of the drawings, the arch 14 is shaped to fit beneath the hollow of the instep of the foot. Normally, when the weight of the person is deposited on the cushion within the shoe, the cushion is depressed most under what may be termed the bony structure of the 105 foot, particularly under the heel and along the outer edge of the foot. The immediate effect of this action is to partially transfer the air from these portions of the cushion to increase the volume below the arch of 110 the foot, where the flesh is softer and more yielding. The result of this is that the hol-

low below the instep of the foot, or what may be termed the arch of the foot, is comfortably and naturally supported. At no time is the arch, when thus supported, called upon to bear a disproportioned part of the weight of the body, as so often occurs in what is termed mechanical arch supports.

From the foregoing it will be seen that by decreasing or increasing the thickness of the arch and heel of the cushion, the apparent height of the person may be correspondingly varied. Also, it is obvious that, as the cushion is concealed within the shoe, the odium attached to the employment of a mechanical help for this purpose, is avoided.

Claims:

1. A device as characterized which may be attached to the shoe if desired, comprising an air-filled cushion having continuous, yielding walls, said cushion having a relatively thin forward portion and a relatively

thick rear portion, the side walls of said rear portion being reinforced to restrain the same from collapsing vertically.

2. As an article of manufacture, a device 25 as characterized having a yielding wall forming an air-filled chamber, being arranged to form a relatively thin forward portion and a relatively thick rear portion, said rear portion having at the inner edge 30 of said device a raised portion to fit beneath, for supporting, the arch of the foot, and vertical walls for said rear portion said walls being strengthened to restrain the crushing effect thereon.

In testimony whereof I have signed my name to this specification in the presence of two subscribing witnesses.

LOUIS DE OLIVA DEOL.
